US00D749173S

(12) **United States Design Patent**
Walker et al.

(10) **Patent No.:** **US D749,173 S**
(45) **Date of Patent:** **** Feb. 9, 2016**

(54) **DRAWING TOOL**

(71) Applicant: **WobbleWorks, Inc.**, Wilmington, DE (US)

(72) Inventors: **Thomas Walker**, Shenzhen (CN); **Peter Dilworth**, Somerville, MA (US); **Maxwell Bogue**, Wellesley, MA (US); **Daniel Cowen**, Hong Kong (CN)

(73) Assignee: **WobbleWorks, Inc.**, Wilmington, DE (US)

(**) Term: **14 Years**

(21) Appl. No.: **29/502,355**

(22) Filed: **Sep. 15, 2014**

(51) LOC (10) Cl. **19-06**

(52) U.S. Cl.

(57) **CLAIM**

The ornamental design for a drawing tool, as shown and described.

DESCRIPTION

FIG. 1 is a front, top perspective view of a drawing tool showing our new design;

FIG. 2 is a rear, bottom perspective view thereof;

FIG. 3 is a top plan view thereof;

FIG. 4 is a bottom plan view thereof;

FIG. 5 is a left side elevational view thereof;

FIG. 6 is a right side elevational view thereof;

FIG. 7 is a front elevational view thereof; and,

FIG. 8 is a rear elevational view thereof.

The broken lines in the Figures show portions of the drawing tool which form no part of the claimed design.

1 Claim, 4 Drawing Sheets
